UNITED STATES PATENT OFFICE.

JOSEPH HOOK, OF MOOSIC, PENNSYLVANIA.

CHOCK-BLOCK.

1,203,340.

Specification of Letters Patent. Patented Oct. 31, 1916.

Application filed August 12, 1916. Serial No. 114,628.

To all whom it may concern:

Be it known that I, JOSEPH HOOK, a citizen of the United States, residing at Moosic, in the county of Lackawanna and State of Pennsylvania, have invented certain new and useful Improvements in Chock-Blocks; and I do hereby declare the following to be a full, clear, and exact description of the invention, such as will enable others skilled 10 in the art to which it appertains to make and use the same.

This invention relates to railway brakes, and more especially to chock blocks; and the object of the same is to produce an improved brake of this kind adapted especially for mining cars and so constructed that when in use it cannot turn at an angle or become derailed and when not in use it occupies a minimum of space.

20 Details will be found in the following specification, reference being had to the drawings wherein:—

Figure 1 is a left side view of this device as its parts stand when it is in use. Figs. 25 2 and 3 are perspective views with the arms respectively raised and lowered. Fig. 4 is a sectional detail showing the fastening of the closure. Fig. 5 is a section on the line 5—5 of Fig. 1. Fig. 6 is a sectional detail 30 of a slight modification.

The base or tread of this chock block comprises a shoe 1 beveled off at its rear end as at 2, its front end or toe 3 being beveled on its under side as at 4, and across the upper face of the shoe is secured or formed thereon an upstanding rib 5 whose front end is undercut or hooked so as to leave an opening 6. Secured along one edge of the shoe is a flange 7 which has a shoulder 8 where it 35 extends past the rib, its upper edge being beveled off as at 9 in rear of said shoulder and its front end being deflected outward as at 10.

The parts thus far described may all be 45 formed of one piece of metal, and the lower face of the shoe is intended to travel on the ball of the rail R while the wheel W is intended to ride up over the shoe 1 and rest against the rib 5. The chock block is connected by a chain C with some part of the car as usual, the chain being connected with the front end or toe 3 of the shoe in any suitable manner as by means of a clevis 11 mounted thereon as seen in the drawings, 50 and when the car is drawn along the rail it is obvious that the wheel will rest on the

chock block while the lower face of the shoe slides along the ball of the rail and the flange against its edge. The upper edge of the flange is beveled off as at 9 to permit 60 the flange of the wheel to pass down beside it as will be clearly understood, and the front end of the flange 7 is bent outward as at 10 so that it will ride alongside the rail while the toe 3 is beveled on the under 65 side as at 4 so that it will ride over rail joints.

Experience has proven that, despite the engagement of the wheel flange with the chock block and of the flange on the latter 70 with the rail, these blocks do often twist out of place and become detached; and in order to avoid this contingency I make use of a guide for so locking the chock block to the wheel that it cannot move relatively thereto, and therefore as long as the wheel over- 75 lies the rail the block will. This guide is of general U-shape formation, comprising inner and outer arms 12 and 13 connected by a shaft 14 which passes through a throat 6 80 of the hook-shaped rib 5. For preventing its escape therefrom I make use of a closure 15 which may well be a block secured upon the front end of the shoe as by bolts or screws 16 to render it removable 85 when the guide is to be taken out for any reason. It will be seen from the plan view in the drawings that the distance between the arms 12 and 13 is greater than the combined width of the shoe 1 and flange 7, and 90 therefore the shaft 14 may both rotate and reciprocate. On that end of the rib opposite the shoulder 8 is formed a projection or lug 17 whose use is best seen in Fig. 5.

Normally the parts stand as in Fig. 1, 95 with the arm 12 resting on the shoulder and therefore the entire guide standing parallel with the upper face of the shoe, and in this position the chock block occupies the least possible space and can be stored with ease. 100 When it is to be used the entire guide is moved by sliding the shaft 14 in the opening 6 so as to free the guide arm 12 from the shoulder, then both arms are raised, and finally the other guide arm 13 is pressed 105 inward against the rib 5 above the lug 17, at which time the arms will stand oblique to the shoe and will extend alongside the wheel W. The latter now rests on the shoe 1 and against the rib 5 and its flange passes 110 down alongside the flange 7 of the chock block with the result that the position of

the wheel on the shoe is such that the guide cannot move laterally through the rib and therefore the arm 13 cannot disengage the lug 17. Hence both arms of the guide are 5 maintained in a raised position alongside the wheel, and the chock block as a whole cannot move laterally with respect to the wheel.

I have shown the shaft 14 as square, and if so it must fit the opening rather loosely. 10 In Fig. 6 the square shaft 14' stands a little bias to the length of the guide arms 12', and the closure 15' is adjustable toward the rib 5' by means of a set screw 16'. With this construction of the device it is obvious that 15 when the guide arms are raised so that the square shaft has its faces parallel with those of the square opening 6', adjustment of the closure by means of the set screw clamps two opposite faces therein and holds the guide 20 raised irrespective of its engagement with the lug 17 which latter may therefore be used or not, although for safety sake I prefer to use it in any case.

With this construction of my device, as 25 with that above described, the normal or storage position of parts is with one arm overlying the shoulder 8 so as to occupy the least space, but the working position is with both arms oblique to the shoe so that the 30 guide straddles the wheel and the chock block is prevented from lateral movement with respect to the same. When the device is not in use the chain C is disconnected from the truck or other point of attachment 35 and the entire article removed and laid aside.

What I claim is:

1. In a chock block, the combination with a shoe, and a raised rib thereon; of a guide 40 movably mounted through said rib and having arms adapted to lie parallel with the shoe or be raised above the same alongside the wheel, and means for holding them raised.
- 45 2. In a chock block, the combination with a shoe having a raised rib, and a flange alongside the shoe and having a shoulder alongside the rib; of a guide movably mounted through said rib and having arms 50 adapted to lie parallel with the shoe and

one of them upon said shoulder or to be raised so as to stand astride the wheel, and means for holding them raised.

3. In a chock block, the combination with a shoe, a raised rib thereon having a trans- 55 verse opening, and a flange along one side of the shoe provided with a shoulder extending alongside said rib; of a shaft rotatably mounted in said opening and of greater length than the rib so that it may be slid 60 through such opening, arms fast on the ends of the shaft and one of them adapted normally to rest on said shoulder, and a lug on the rib adapted to be engaged by one of said arms when the latter are raised.

4. In a chock block, the combination with a shoe, a raised hook-shaped rib thereon, a closure over the throat of said hook, and means for fastening the closure in place; of a shaft loosely mounted in the throat of the 70 hook, parallel arms projecting rigidly from the ends of said shaft, and means for holding them elevated at an angle to the shoe.

5. In a chock block, the combination with a shoe, an upstanding hook-shaped rib upon 75 the same, a closure for the throat of said hook, the parts being shaped to produce a rectangular opening, and means for adjusting the position of the closure; of a guide including a pair of arms and a rectangular 80 shaft connecting their forward ends and extending through said opening, for the purpose set forth.

6. A chock block comprising a shoe beveled off on its upper face on its rear end and 85 having its toe beveled off on its under face, a clevis on said toe, a flange secured to one side of the shoe and beveled off at the upper edge at its rear end, shouldered forward of said bevel, and deflected outward at its 90 front end, and a rib rising from the shoe opposite said shoulder; combined with a guide movably mounted in said rib and comprising a pair of arms adapted to stand parallel with the shoe or oblique thereto and 95 astride a car wheel.

In testimony whereof I affix my signature.

JOSEPH HOOK.
